UNITED STATES PATENT OFFICE.

MARTIN KAUFMAN, OF NEW YORK, N. Y.

TOILET PACKAGE.

Application filed February 13, 1922. Serial No. 536,068.

To all whom it may concern:

Be it known that I, MARTIN KAUFMAN, citizen of the United States, residing at New York, in the county of New York and 5 State of New York, have invented certain new and useful Improvements in Toilet Packages, of which the following is a specification.

This invention relates generally to toilet 10 requisites, having more particular reference to a combination package containing requisites for the bath.

The invention has for a general object to provide a novel toilet package of this kind, 15 and also, in general terms, to provide for increased invigorating effect from the bath and the imparting to the body of the odor of a flower essence. More specifically speaking the invention has for an object to provide a 20 package comprising a jar or bottle containing perfumed sea salt into which is set a small bottle containing a concentrated flower essence.

For further comprehension of the invention, and of the objects and advantages thereof, reference will be had to the following description and accompanying drawings, and to the appended claims in which the various novel features of the invention 25 are more particularly set forth.

Fig. 1 of the drawings is a side elevation of my improved package.

Fig. 2 is a fragmentary vertical sectional view thereof, taken on the line 2—2 of 30 Fig. 1.

Fig. 3 is a similar view of Fig. 2, but showing a modification.

Fig. 4 is a like view of a further modification.

Fig. 5 is a top plan view of the bottle shown in Fig. 4.

Fig. 6 is a detail side view showing another form of bottle for containing the concentrated flower essence.

Referring now particularly to Figs. 1 and 2 the reference numeral 10 indicates a jar, preferably of glass and having a neck 11 forming a mouth which is closed by a cap also preferably of glass, the neck and cap being here shown as formed with co-operating coarse screw threads 13 which are so arranged as to lock the cap in place by a single turn, or partial turn after the flange of the cap has been inserted a distance into 50 the neck.

This jar 10 is filled with sea salt, indi-

cated at 14, which is preferably perfumed prior to placing in the jar. As the perfume tends to dissipate if the package stands for any considerable length of time, as may 60 happen between the time of preparation and the time it reaches the consumer, I insert in the top of the jar a small bottle 16 containing a concentrated flower essence similar to that initially applied to the salt, the body 65 of this bottle being embedded in the salt as shown, the mouth of the bottle being closed by an ordinary cork 17 covered by a seal 18.

The construction shown in Fig. 3 differs from that shown in Figs. 1 and 2 only in 70 the formation of a recess in the cap 12' into which the cork 17 of the bottle is inserted and in which it is held by a suitable medium such as wax, indicated at 21.

In Figs. 4 and 5 I have shown a further 75 modification in which the perfume bottle 16' is of conical shape and provided with a short frusto-conical neck 25 receiving a shallow cork 26. This neck is inserted in a recess in the inner side of the cap 12^a and 80 is held therein by a sealing medium 27 such as wax which is placed in a recess 28 in the cap and acts both to seal the mouth of the bottle and hold the latter in place on the cap, the walls of this recess being tapered as 85 shown so as to prevent accidental dislodgment of the wax seal, and with it the bottle. To prevent chance of breaking of this seal 27 when the bottle is being forced downward 90 into the salt in the jar I provide the cap with lugs 29 adapted to engage in sockets 30 formed on the bottle 16' to securely hold the bottle against relative rotation with respect to the cap. The seal 27, as will be understood, is sufficiently plastic to permit 95 of ready removal of the bottle from the cap 12^a when the contents of the bottle are to be used.

As indicated in Fig. 6 I may employ a bottle having a straight body 31 and a 100 pointed lower end 32 to facilitate the embedding thereof in the salt. This shape of bottle may be used with either of the modifications shown.

When the salts are to be used the cap is 105 removed from the jar, the seal of the bottle of concentrated flower essence broken, and the contents thoroughly mixed with the salts. A small quantity of the salts is shaken 110 into the bath water, and allowed to dissolve, producing an invigorating effect, while the concentrated flower essence, in ad-

dition to imparting a delightful odor to the body has a soothing effect on the skin.

Having thus described my invention what I claim as new and desire to protect by Letters Patent of the United States is as follows:

1. A toilet package comprising a jar-like receptacle substantially filled with sea salt, a cap for said receptacle, and a small bottle 10 of concentrated flower essence carried by said cap, said cap being formed with a recess on its underside into which the top of said bottle projects, and a plastic material set in said recess and acting to hold the bottle 15 on the cap and seal the mouth thereof.
2. A toilet package comprising a jar-like receptacle substantially filled with sea salt, a cap for said receptacle, and a small bottle 20 of concentrated flower essence carried by said cap, said cap being formed with a recess on its underside into which the top of said bottle projects, and a plastic material set in said recess and acting to hold the bottle 25 on the cap and seal the mouth thereof, said bottle being of conical shape.
3. A toilet package comprising a jar-like receptacle substantially filled with sea salt, a cap for said receptacle, and a small bottle 30 of concentrated flower essence carried by

said cap, said cap being formed with a recess on its underside into which the top of 30 said bottle projects, and a plastic material set in said recess and acting to hold the bottle on the cap and seal the mouth thereof, said bottle being of conical shape, and 35 co-operating devices on said cap and bottle holding said bottle against rotation on said cap.

4. A toilet package comprising a jar-like receptacle filled with sea salt, a screw-cap 40 for said receptacle, a small bottle of concentrated flower essence attached to the underside of said cap, and a plastic material acting to hold the bottle on the cap and seal the mouth thereof.

5. A toilet package comprising a jar-like receptacle filled with sea salt, a screw-cap 45 for said receptacle, a small bottle of concentrated flower essence attached to the underside of said cap, and a plastic material acting to hold the bottle on the cap and seal the mouth thereof, and co-operating devices on said cap and bottle holding said bottle 50 against rotation on said cap.

In testimony whereof I have affixed my 55 signature.

MARTIN KAUFMAN.
